WORK REMOVING APPARATUS FOR PRESSES

Henry Sahl, Detroit, Mich., assignor to General Motors Corporation, Detroit, Mich., a corporation of Delaware

Application September 19, 1940, Serial No. 357,453

5 Claims. (Cl. 113—50)

This invention relates to material handling and has for its object material ejecting apparatus designed to be used with metal stamping presses and to be automatically operated by the press and particularly by the up and down movement of the ram of the press.

Referring to the drawings:

Fig. 1 is a side elevation of the apparatus shown in connection with a press, the latter being shown in a sketchy diagrammatic way.

Fig. 2 is a similar view of the apparatus after the work has been released from the die and the apparatus has gripped the work.

Fig. 3 is a similar view of the apparatus as the same is in process of pulling the work out of the press.

Fig. 4 is a detail view of the gripping arm, together with the gripping jaws in open position.

Fig. 5 is a similar view showing the jaws in closed position.

Fig. 6 is a section on the line 6—6 of Fig. 5.

1 designates the ram of the press and 2 designates the bed of the press. The ram is provided with a suitable punching die 3 and the bed of the press with a suitable female die 4. This has a portion 5 which acts as a knock-out or release at the proper time. The usual knock-out pins may be substituted for this arrangement. A knock-out, however, is not always required because in some instances the work hand itself can be used as a knock-out device.

A heavy pendant arm 6 is pivoted at 7 and, when not actuated, swings down to the vertical position shown at 8 in Fig. 3, a stop 9 being provided to prevent its overswinging against the press. This arm carries the work gripping arm 10 which is provided with two jaws 11 and 12, each provided with a toothed or serrated gripping piece 13 removably secured in place by screws 14. The upper jaw is arranged to slide 40 in the guideway 15 on the arm 10. The lower jaw is in the form of a bell crank lever and is pivoted at 16 to the sliding upper jaw member. The sliding upper jaw is connected to the end of a piston rod 17 which, in turn, is connected to piston 18 that slides in cylinder 19. Spring 20 tends to keep the piston to the left of its stroke. Pipe 21 connects with the left hand end of the cylinder. Pin 22 holds the bell crank lever or lower jaw member 11 in the open position shown in Fig. 4.

The operation of the machine is as follows: A piece of sheet metal having been put between the dies, the ram of the press is caused to descend in the usual way and stamps the metal, as shown 55

in Fig. 1, where the work is designated W. As the ram rises, the knock-out portion 5 of the female die rises relatively to the lower die (as is shown in Figs. 2 and 3). This knocks out or releases the work W. As the ram rises, the cam 24 strikes the trip arm 25 that controls the fluid valve 26. This allows fluid to pass through pipe 21 to the left end of cylinder 19, causing piston 18 to travel to the right (as shown in Fig. 5). This causes the open jaws 11 and 12 to straddle the edge of the work which has been knocked out of the lower die (as shown in Fig. 2). As the jaws are pushed to the right to straddle the work, the upper arm 28 of the bell crank lower arm 11 strikes the shoulder 27 at the end of the arm 15. This causes the lower jaw to revolve on pivot 16 counter-clockwise and thereby the jaws are brought together to grip the work. As the ram rises, the projecting roller 29 strikes the upper end 30 of the pivoted arm 6. This has a cam surface 31 adapted to ride along the roller 29 and the arm is caused to swing out to the dotted line position shown in Fig. 3 where the arm is over the traveling conveyor 32. At this point, the trip arm drops off cam 24 on the side of the ram, as shown by the dotted line position A in Fig. 3. This allows the spring 33 to return the fluid control valve to the released position and allows the air to exhaust through the valve, as shown by the arrows in Figs. 1 and 3. Spring 20 returns piston 18 to the left hand position (as shown in Fig. 4) and the jaws separate (as shown in Fig. 4 and in dotted lines in Fig. 3). This drops the work onto the conveyor 32 which is continuously moving.

It is possible, by altering the cam surfaces, to swing the arms 6 out to substantially horizontal position where the work will be dropped in such a way that it inverts itself, if this be desired.

I claim:

1. In an apparatus for removing work from a press or other like machine, the combination with two relatively movable members such as the ram and bed of a press, a swinging pendant arm supported at the side of the machine and having at its lower end a pair of jaws for gripping the work, the movable member of the machine arranged in its upward movement to cause the pendant arm to swing upwardly and outwardly into a position away from the press and means for causing the jaws to grip the work before the arm swings upwardly and to drop the work free from the press as the pendant arm reaches the outward end of its movement.
2. In an apparatus for removing work from a

press or other like machine, the combination with two relatively movable members such as the ram and bed of a press, a swinging pendant arm supported at the side of the machine and having at its lower end a pair of jaws for gripping the work, the movable member of the machine arranged in its upward movement to cause the pendant arm to swing upwardly and outwardly into a position away from the press and means for causing the jaws to grip the work before the arm swings upwardly and to drop the work free from the press as the pendant arm reaches the outward end of its movement, the said last mentioned means comprising a piston and cylinder connected with the jaws for operating the jaws, said cylinder furnished with fluid automatically controlled by the movement of the movable member of the machine.

3. In an apparatus for removing work from a press or other like machine, the combination with two relatively upwardly and downwardly movable members such as the ram and bed of a press, a swinging pendant arm supported at the side of the machine and having at its lower end a pair of jaws for gripping the work, the movable member of the machine arranged in its upward movement to cause the pendant arm to swing upwardly and outwardly and means for causing the jaws to grip the work before the arm swings upwardly and to release the work as the pendant arm reaches the outward end of its movement, the said last mentioned means comprising a pair of jaws which slide with respect to the arm and one of which is pivoted to the other and provided with an arm portion arranged to be tripped by a shoulder, a piston and fluid cylinder with the piston connected to the sliding jaws to cause the jaws to advance upon the work and straddle the same and the pivoted jaws with the trip arm arranged to engage a shoulder on the pendant arm to cause the pivoted jaws to close one upon the other and upon the work and fluid control means controlled by the movement of the movable member of the press.

4. In an apparatus for removing work from a

press or other like machine, the combination with two relatively upwardly and downwardly movable members such as the ram and bed of a press, a swinging pendant arm supported at the side of the machine and having at its lower end a pair of jaws slideable at a unit on the arm and for gripping the work, the movable member of the machine arranged in its upward movement to cause the pendant arm to swing upwardly and outwardly and means for causing the jaws to move independently of the arm to straddle the work and to grip the work before the arm swings upwardly and to release the work as the pendant arm reaches the outward end of its movement, the said last mentioned means including a fluid cylinder and piston for causing the jaws to slide with respect to the arm to close upon the work and to release the work and a fluid valve supported adjacent the side of the machine and having a trip arm and a cam on the movable member of the machine for engaging the trip arm to control the valve which controls the fluid to the piston.

5. In an apparatus for removing stampings from a press, the combination with a machine having a bed and a movable ram having a trip member of a pendant arm pivoted at its upper end and having a portion of the upper end of the arm forming a cam surface to be struck by the member on the ram to swing the arm and the work out from the machine, the lower end of the arm extending at an angle to the pendant portion of the arm and slideable jaws slideable on said arm end and one pivoted with respect to the other and a fluid cylinder and piston for advancing the jaws to a straddling position on the work and one of the jaws pivoted and provided with a trip portion adapted to engage a stationary portion of the arm when the jaws have been slidably advanced to the straddling position to cause the jaws to close upon the work and a valve in proximity to the ram and controlled by the movement thereof to regulate the fluid supply and the exhaust from the fluid cylinder.

HENRY SAHLIN.
